PHONOGRAPH STYLE

John M. Dean, Jr., Putnam, Conn.

Application June 9, 1937, Serial No. 147,328

2 Claims. (Cl. 274—38)

This invention relates to an improved style or needle for use with sound-reproducing instruments such as phonographs and the like.

One object of the invention is to provide a needle of the type indicated which will play a large number of records without distortion in the sound reproduced thereby.

Another object of the invention is to provide a needle of the type indicated which will play a large number of records without abrading or scoring the records to cause distortion of the sound reproduced thereby.

Another object of the invention is to provide a novel form of style or needle which will follow the sound-track or groove of the record without bearing against the upper edges thereof or on the top of the record to cause wear thereon.

Another object of the invention is to provide a one-piece style or needle of the type indicated having a substantially flat-sided, pointed end of a thickness to fit the groove in the record in such manner as to prevent wearing shoulders on the needle.

Another object of the invention is to provide a style or needle having its record-engaging portion of concavo-convex shape in cross-section formed to the mean radius of the record groove to adapt the needle to traverse the latter without scratching or scoring and providing for a more sensitive response to the undulations of the sound-track.

Further objects of the improvement are set forth in the following specification which describes a preferred form of construction of the style or needle as illustrated in the accompanying drawing. In the drawing:

Fig. 1 is an elevational view of the sound-box of a conventional type of phonograph showing the present improved needle applied to the socket thereof with its point engaging the sound-track of a record on the turntable of the phonograph;

Fig. 2 is an enlarged transverse sectional view of the sound-box support or socket for the needle taken on line 2—2 of Fig. 1 and showing the needle in place therein with its point engaging the sound-track of the record, also illustrated in section;

Fig. 3 is a fragmentary plan view of the record shown as greatly enlarged and illustrating the concavo-convex shape of the pointed blade of the needle in section on line 3—3 of Fig. 2;

Fig. 4 is a greatly enlarged view of the improved needle showing the flat-sided blade at its point; and

Fig. 5 is a similar view looking towards the thin edge of the flat blade of the needle.

The commonly used style or needle for phonographs and like sound-reproducing instruments is formed of cylindrical steel rod or wire tapered

to a point at one end to adapt it to enter the groove or sound-track of the record. The life of such a form of needle is very short, it being advisable to discard and replace the needle after the playing of each record in order not to spoil the record by the abrasive action of the needle thereon. Considerable friction is engendered during the traverse of the needle in the sound-track and as the material of the record is relatively hard and flinty it causes abnormal wear on the sides of the point of the needle. That is to say, the point is worn down on its sides which causes the formation of shoulders and these shoulders bear against and scrape the top of the record to cause damage thereto. Moreover, the shoulders eventually prevent the point of the needle from bottoming in the sound-track or groove of the record and therefore accurate and true-toned reproduction is impossible with such a worn needle.

The present invention has for one of its objects to provide a needle not subject to wear and the forming of shoulders on its sides liable to abrade and scratch the top of the record. To accomplish this result the point of the needle is flattened on opposite sides or, preferably, made substantially flat with a concavo-convex shape in cross-section as later more fully explained. My improved needle is thus rendered capable of playing more than a hundred records without being worn away on the sides of its point to form shoulders liable to damage the record or to interfere with the proper reproduction of the sound. The present improved needle is therefore well adapted for use in phonographs having automatic record-changing mechanisms as it can be used repeatedly for more than a hundred records without replacement as is necessary with most types of needles. Heretofore, automatic record-changing instruments have usually required the use of a special form of needle having a tip of harder metal or, in some cases, a jewel point to resist wear during its use. Such a type of needle is expensive to manufacture while my present improved needle is relatively cheap to produce and has practically all the advantages of the hard-tipped needle.

Referring first to Fig. 1 of the accompanying drawing, 2 designates the sound-box at the end of the tone-arm 3 of a conventional type of phonograph comprising the usual rotary turntable 4. The recter, designated R, rests on the turntable 4 and the needle 5 is shown as held in a socket 6 on the sound-box 2 by means of the usual thumb-screw 7, see also Fig. 2.

Referring to Figs. 4 and 5, the present improved needle comprises a body portion 10 of substantially cylindrical shape adapted to seat in the hollow of the sound-box socket 6 and to be clamped in place by the end of the set-screw 7.

impinging thereagainst. The cylindrical portion 10 of the needle 5 is herein shown as of slightly more than one-third of its whole length with the remainder of the needle continued 5 downwardly at 11 with a relatively gradual taper terminating in the point 12. At a distance downwardly from the joiner of the shank with the tapered portion 11 the needle is ground or otherwise flattened on its sides to form a relatively 10 thin tapered blade 14. Preferably, instead of grinding or forming the sides of the point in flat planes the blade 14 is shaped to concavo-convex form in cross-section, as shown in Fig. 3, on a radius corresponding substantially to the mean 15 radius of the sound-track on the record with which it is to be used. The purpose of this concavo-convex formation of the pointed end of the needle is to provide that it will conform substantially to the curvature of the sound-track which 20 it traverses during the rotation of the record.

It will be noted by reference to Fig. 5 of the drawing that the two opposite sides of the flattened or concavo-convex shaped blade 14 of the needle are parallel. The blade 14 is made of 25 slightly less thickness than the width of the groove or sound-track, indicated at *t* in Figs. 2 and 3, so that the needle may have a slight clearance therein. Conventionally, the sound-track is from .006 to .007 of an inch in width and the 30 blade 14 of the needle is preferably made .005 of an inch thick. The tip 12 of the needle, while relatively sharp, is preferably smoothed off or slightly rounded to prevent it from digging into the bottom of the groove of the record.

35 The present improved needle is applied to use by placing it in the socket 6 of the sound-box 2 with the flattened sides of its blade-portion 14 extending longitudinally of the sound track or groove *t* in the record, see Figs. 1, 2 and 3. The 40 needle is clamped in place by screwing the thumb-screw against its side and, preferably, the body or cylindrical portion 10 of the needle is flattened off on its side corresponding to one of the flattened sides of its blade-portion 14 to insure that it is 45 properly placed in the sound-box socket.

The point of the needle is placed in the sound-track *t* of the record *R* and as the latter is rotated with the turntable 4 the needle will traverse the sound-track or groove *t* with a smooth undulatory motion without any tendency to scrape the sides of the groove or to impinge against the upper edges thereof. That is to say, the blade-portion 14 of the needle will conform substantially to the curvature of the sound-track or 55 groove *t* to travel smoothly therein without scratching or abrading the walls of the groove. Moreover, as the tip 12 of the needle point wears down the blade-portion 14 of the needle will simply sink deeper into the groove *t* of the record 60 without contacting the upper edges of the walls of the groove. In this way the point of the needle is relieved of any wear tending to form shoulders on its sides and consequently it will always bottom in the groove even after considerable 65 wear on its point. By preventing the formation of shoulders on the sides of the needle the upper edges of the groove in the record are saved from abrasive action and consequently the record will not be damaged by repeated use of the same 70 needle as is the case when needles of the type commonly used are employed for playing more than one record. It will thus be seen that the present improved needle may be used repeatedly in the phonograph or other sound-reproducing 75 instrument without deterioration and without

causing wear on, or damage to, the record liable to distort the sound reproduction thereof. It has been determined in practice that the present improved needle will play more than one thousand records without replacement with accurate tone 5 reproduction and without abrasive action or wear on the record.

As another important feature of improvement in the present needle it will be noted that the frusto-conical or tapered portion 11 which extends between its main body 10 and the blade 14 is of substantial structure to prevent undue vibration in that part of the needle which projects below the socket 6 of the sound-box. In other words, the blade-portion 14 of the needle is relatively short as compared with the length of its supporting portion 11 and this latter portion has the effect to stiffen the point of the needle to prevent vibrations which would distort the sound being reproduced. 20

From the foregoing it will be observed that the present invention provides an improved form of style or needle for phonographs and like sound-reproducing instruments which is much more durable in use than common types of needles 25 heretofore used; which may be used repeatedly without undue wear or injury to the record; and the use of which results in more perfect tone reproduction from the record being played.

While the improved style or needle is herein 30 shown in a preferred form of construction, it is to be understood that slight changes may be made in its shape and proportions without departing from the spirit or scope of the invention. Therefore, without limiting myself in this respect, I claim:

1. A phonograph style or needle for cooperation with records having hill-and-dale sound track grooves, said needle constructed with a body portion of cylindrical form and a portion extending downwardly therefrom and gradually tapered to a point, a considerable proportion of the length of said tapered extension being cut away on its sides to form a relatively thin blade, said blade being of somewhat less thickness than the width 45 of the groove in the record with which it is used to adapt it to fit between the sides of the groove with a slight clearance and of a length greater than the depth of the groove to adapt its pointed end to bottom therein, one side of the blade portion being concave and the other side being convex on a radius conforming substantially to the mean radius of the groove in the record.

2. A phonograph style or needle for cooperation with records having hill-and-dale sound track 55 grooves, said needle consisting in a cylindrical body-portion continued downwardly in an extension tapering gradually to a point with a considerable proportion of the length of the tapered extension cut away on its sides to provide a thin 60 blade with substantially flat parallel faces, said blade being of a length greater than the depth of the sound grooves in the record to adapt its pointed end to bottom therein with its sides conforming to the sides of the groove, and the body 65 portion of the needle having a flat face parallel with the flat sides of the blade to adapt it to be engaged by the set-screw in the socket of the sound-box to hold the flat sides of the blade in position parallel with the sides of the sound track 70 groove of the record whereof the needle may travel smoothly therein with its point engaging the bottom of the groove.
